UNITED STATES PATENT OFFICE.

EDWARD E. VOGLER, OF ST. LOUIS, MISSOURI.

DESIGN FOR A LAMP STAND.

Application filed October 27, 1924. Serial No. 11,194. Term of patent 7 years.

To all whom it may concern:

Be it known that I, EDWARD E. VOGLER, a citizen of the United States, residing at St. Louis, State of Missouri, have invented a new, original, and ornamental Design for Lamp Stands, of which the following is a specification, reference being had to the accompanying drawing, forming a part thereof.

Figure 1 is a top plan, and Figure 2 is a perspective view of a lamp stand showing my new design.

I claim:

The ornamental design for a lamp stand as shown.

EDWARD E. VOGLER.

Witnesses:

ELLA R. YAVITZ,
HARRY A. BEIMES.
